WINDING MACHINE

August D. Eitzen, Rockville Center, N. Y., assignor
to News Projection Corporation, New York,
N. Y., a corporation of New York

Application January 10, 1929, Serial No. 331,615
Renewed May 31, 1933

10 Claims. (Cl. 242—55)

My present invention relates generally to winding machines, and has particular reference to a machine for winding ticker tape.

Although I have herein illustrated and shall 5 hereinafter describe my invention as applied to the winding of ticker tape as the same is fed from a particular type of display apparatus, nevertheless it will be understood that as to certain phases of my invention such an application is not essential.

It is a general object to provide a machine for winding ticker tape into a firm spiral roll by mechanism which is extremely simple in construction, highly efficient in operation, and which 15 necessitates a minimum of attendance and control.

It is a particular object of my present invention to provide a machine wherein the formation of a spiral roll is accomplished without any recourse to a mandrel or spindle upon which such roll is formed. Since the tape supplied to any winding machine is fed at a substantially uniform rate of speed, it follows that any mandrel arrangement is beset with the difficulty of adjusting the rotative speed of the mandrel to the 20 gradually increasing diameter of the spiral wound thereon. In other words, the peripheral velocity of such a roll should remain substantially uniform, and if the roll is being wound by means of a torque applied to a mandrel, the speed of 25 rotation of such mandrel must be gradually reduced as the diameter of the roll increases. Such reduction of speed has heretofore been accomplished by means of slippage devices interposed 30 between the mandrel and its driving instrumentality. My present invention obviates the necessity for providing any such slippage device.

The spiral roll produced in accordance with my present invention is built upon a nucleus 40 formed of the tape itself and it is caused to rotate by means of a force or forces applied to the periphery of the roll. Since the peripheral speed is substantially uniform, I am enabled to employ a constantly moving belt which frictionally engages the roll over a substantial arc of 45 the periphery, and I am enabled to move this belt at a substantially uniform speed.

Briefly, my invention resides in the provision 50 of means for engaging the tape which is supplied from the ticker or the like, means for directing the end of the tape against suitable means for doubling such end back under itself so as to form the nucleus of a spiral, and means such as the belt previously referred to for frictionally engag-

ing the periphery of the spiral roll to support and rotate the same.

Certain outstanding features of my invention 55 reside in the arrangement of parts and mechanism for keeping the spiral roll constantly in a tightly wound condition, the provision of means for continuing the machine in operation despite the growth of the spiral roll, means whereby the relatively large ultimate roll automatically positions itself in an accessible manner to permit 60 easy withdrawal thereof, and means for so engaging and directing the tape that it need only be fed into the machine, as through a slot or the like, in order that the operation may commence.

In order that the means for engaging and advancing the tape may be prevented from causing a breakage in a case wherein the tape supply is suddenly retarded or stopped, I provide a slippage arrangement which permits the advancing 75 means to halt without interfering with the motive power or the subsequent smooth operation. I wish to point out, however, that this slippage arrangement is not of the character hereinbefore referred to in connection with mandrel-driven 80 machines, since it comes into operation only when the supply of tape is stopped. During normal winding conditions, there is no slippage whatsoever in any portion of my machine.

For the attainment of the foregoing objects and 85 such other objects as may hereinafter appear or be pointed out, I have illustrated one form of my invention in the accompanying drawings, wherein—

Figure 1 is an elevational view showing a winding machine of the present character associated 90 with a particular type of display device through which the ticker tape is passed;

Figure 2 is an enlarged vertical cross-sectional view through the winding machine, this view being 95 taken in the same direction as Figure 1;

Figure 3 is a view of the winding machine as it appears when viewed from the left of Figure 2;

Figure 4 is a cross-sectional view taken substantially along the line 4—4 of Figure 2; 100

Figure 5 is a fragmentary cross-sectional view taken in the same direction as Figure 2 and showing certain vital parts in positions other than those shown in Figure 2; and

Figure 6 is a fragmentary perspective view of 105 certain parts of the machine to illustrate their cooperation.

In Figure 1 I have shown one end portion of a stock quotation ticker 10 or the like from which a ticker tape 11 is fed in a wellknown manner. 110

The tape 11 is typical of that type of tape for which my winding machine is particularly adapted. I have shown this tape entering, passing through, and leaving a projecting apparatus 12, 5 the latter having a source of light which is projected upwardly through the tape and through a suitable objective lens 13 to display the markings on the tape in a suitable manner upon a screen. At the right of Figure 1 I have shown the 10 tape 11 leaving the device 12 and entering the winding machine proper.

Referring to Figure 2 I will point out in a general way that my winding machine comprises a main casing 14 and an auxiliary casing 15 attached to one side thereof, as shown most clearly in Figure 3. Mounted in the casing 15 and upon a shaft 16 is a feeding wheel 17 adapted to rotate in the direction of the arrow of Figure 2. A suitable opening 18 is provided in the wall of 20 the casing 15 to permit the tape 11 to enter the casing 15 and to pass around the lower half of the periphery of the wheel 17. The latter is provided with a circumferential groove 19 whose function will be presently described.

25 Carried by a pin 20 which is secured within the casing 15 adjacent to the wheel 17 is a spring wire or the like 21 adapted to overlie the lower portion of the periphery of the wheel 17. In fact, the spring 21 overlies the lower portion of the 30 groove 19. The wheel 17 is of a width approximately equal to the width of the tape 11, and the latter is securely gripped between the periphery of the wheel 17 and the spring 21 as shown most clearly in Figure 4. This grip insures a frictional engagement between the wheel 17 and the tape 11 so that the latter will be advanced in the direction of rotation of such wheel, forming a tape drawing means.

Before describing other portions of my device 40 I will point out that the wheel 17 is driven at a substantially uniform rate of speed from the motor 22 whose driving shaft is provided with the worm 23 which extends into the casing 14. Meshing with the worm 23 is a worm wheel 24 mounted 45 upon a shaft 25. The latter shaft carries a worm 26 which meshes with a worm wheel 27. The wheel 27 is axially aligned with the shaft 16 of the wheel 17, but is not directly connected thereto. Upon referring to Figure 4, it will be 50 noted that the wheel 27 is a portion of a sleeve 28 freely rotatable about the shaft 16.

The sleeve 28 carries also the spur gear 29 whose function will be presently described. Engaging 55 with the outer face of the gear 29 is a friction disc 30 keyed as at 31 to the shaft 16. Similarly engaging with the outer face of the worm wheel 27 is a complementary friction disc 32 splined as at 33 to the shaft 16. Adjustably mounted on the shaft 16 is a nut element 34 adapted to bear 60 against a compression spring 35, the latter engaging the disc 32 to force the same against the wheel 27. This frictional sandwiching of the sleeve 28 between the friction discs 30 and 32 results in normal rotation of the shaft 16 by the wheel 27 65 at the same speed as the latter. Under certain circumstances, hereinafter to be mentioned, the wheel 27 is free to continue its constant rotation without rotating the shaft 16 along with it.

70 Fixedly carried within the casing 15 is a guide strip 36 which is most clearly illustrated in Figure 6 and comprises the upper forked portion formed by the upwardly extending spaced prongs 37, and the lower attenuated portion formed to provide the finger 38 which extends downwardly

75 into the groove 19. The function of this strip 36 will be presently described.

80 Mounted above the casing 15 is a pivotally arranged casing or frame 39 which is open at the bottom. A shaft 40 extends from within the casing 14 into and across the casing 39 to form a pivot axis therefor. A coil spring, such as a clock spring 41, is attached at its outer end, as at 42, to the casing 39 and is attached at its inner end, as at 43, to the casing 14. The spring 41 constantly urges the casing 39 into the normal position shown in full lines in Figure 2.

85 Within the casing 39 and mounted upon the shaft 40 is a pulley 43 designed to rotate in the direction of the arrow of Figure 2 and driven from the motor by means of the spur gear 44, the latter being carried upon the shaft 40 within the casing 14 and meshing with the spur gear 29 previously mentioned.

90 Adjacent the opposite end of the casing 39 is a somewhat smaller pulley 45 mounted upon a spindle 46. The latter is not journaled directly between the opposite walls of the casing 39 but is carried between the arms of a fork 47. The fork 47 is mounted for longitudinal reciprocation 95 within a sleeve 48 fixedly carried within the casing 39. A rearwardly extending bar 49 is carried by the fork 47 and extends through the sleeve 48. A tension spring 50 connects the rear end of the bar 49 with the sleeve 48, thereby tending constantly to urge the bar 49, the fork 47, and hence the pulley 45, outwardly away from the pulley 43. In this way, a friction belt 51 extending around the pulleys 43 and 45 is constantly retained under tension.

100 The belt 51 is driven by the pulley 43 at a uniform rate of speed, which speed is substantially the same as the peripheral speed of the wheel 17. The belt 51 travels in the direction of the small arrow shown adjacent to the pulley 45 in Figure 2.

105 A pin or spindle 52 projects outwardly from the casing 14 slightly below the casing 39 and adjacent to the pulley 43 and serves to force the belt 51 into the position shown in Figure 2 when the casing 39 is in its normal position as shown in Figure 2.

110 Carried by the sleeve 48 and extending toward the pulley 43 is the strip 53 similar in nature to the strip 36 and most clearly shown in Figure 6.

115 The strip 53 is provided with the rear forked portion constituted of the downwardly curved prongs 54.

120 When the casing 39 is in its normal position, the belt 51 passes beneath the strip 53 and between the prongs 54, thence above the strip 36 and between the prongs 37, thence around the pin or spindle 52. As the casing 39 is pivoted, during the operation of the machine presently to be described, toward the dot and dash position 125 of Figure 2, the belt 51 gradually leaves its threaded passage through these prongs 54 and 37, as is most clearly observed in Figure 5 and in the dot and dash lines of Figure 2.

130 The prongs 54 are so shaped and arranged with respect to the upper portion of the strip 36, that a substantially semi-circular pocket is 135 defined, as shown in Figures 2 and 6.

140 In operation, the several parts hereinbefore described, cooperate as follows. The strip 11 is fed inwardly through the opening 18 into a position 145 between the periphery of the wheel 17 and the rear portion of the spring or wire 21. The wheel 17 immediately becomes operative to advance this tape around its lower portion. When the tape

end reaches the finger 38 (after a travel of about 180°), the finger 38 guides the tape off of the wheel 17 and upwardly toward the belt 51. The latter directs the tape end toward the semi-circular pocket above described, and the continued advancement of the tape by the wheel 17 causes the tape end to be doubled back under itself as shown in Figure 2 as this end encounters the pocket referred to. This doubling back of the tape end causes the tape to form the nucleus of a spiral roll, and I will point out at this time that this spiral roll is thus produced without any recourse to a mandrel or the like.

The belt 51 immediately becomes operative not only to rotate the nucleus but to support the latter from above. Such rotation, along with a continuation of the advancement effected by the wheel 17, causes the spiral roll gradually to grow in size. As the diameter increases, the upward pressure upon the belt 51 causes the entire casing 39 gradually to swing upwardly from the full-line position of Figure 2 toward the dot and dash position thereof.

In Figure 5 I have illustrated an intermediate position. The roll is in this figure designated by the reference numeral 55 and is being rotated in the direction of the arrow by means of the belt 51. To serve as a support for this roll at such intermediate stage of its formation and growth, I provide a guide roller 56 mounted upon an arm 57 which is pivoted at its lower end 58 to the casing 15. A tension spring 59 constantly urges the arm 57 to the left thereby keeping the tape 11 in suitable contact with wheel 17 and facilitating the support of the roll 55.

As the roll increases in diameter, the axis thereof gradually shifts from the point at which the nucleus was initially created toward a point upwardly and to the right. After this axis has passed beyond a point substantially over the axis of the roller 56, the roll 55 should advantageously be supported by still further means, and for this purpose I have provided the second guide roller 60 carried by an arm 61 pivoted at 62 to the casing 14. A tension spring 63 tends to keep the roller 60 in a position whereby it yieldably presses or bears radially inwardly with respect to the roll 55. After support is found upon the roller 60, the roll 55 leaves contact with the roller 56, and the latter thereafter serves only the single function of suitably guiding the tape 11 onto the periphery of the roll 55.

In Figure 2 I have shown by means of the dot and dash lines 64 the approximate periphery of the roll 55 after the same has ultimately reached a considerable diameter, almost as large as the machine itself. The roll is at this stage of the operation supported upon the roller 60 which has been gradually forced downwardly into the dot and dash line position illustrated. At the opposite portion of the roll the same is still being rotated and supported by means of the belt 51, the position of which is at this stage of operation illustrated by the dot and dash lines 65.

When the roll has attained the desired size, it is merely necessary to tear the same away from the machine or preferably to sever the tape at a point entering the opening 18. The roll may then be withdrawn in a simple manner and disposed of as desired. As the roll is withdrawn, the parts will all automatically return to their original positions. Thus, the casing 39 will swing back under the action of the spring 41. In doing so, the belt will encounter the spindle 52 and be yieldably forced into the position shown in Figure 2. The

purpose of the spindle 52 is thus obvious, viz., to hold the belt in a position whereby the semi-circular pocket may be provided in the proper position for forming the nucleus of the roll newly to be started.

To start a new roll, no adjustment is necessary other than to feed the end of the tape through the opening 18 in the manner previously described.

Under normal conditions of operation, there is therefore no slippage whatsoever between any driving force such as the motor 22 and the driven parts of the machine. Since the peripheral speed of the spiral roll is constantly substantially uniform, the constant driving of the belt 51 at a uniform speed is sufficient and highly satisfactory for rotating and supporting such roll. Similarly, the constant and substantially uniform advancing action of the wheel 17 is satisfactory for purposes of feeding the tape at a substantially uniform speed onto the periphery of the rotating roll.

To provide for the contingency that the tape supply from the projector 12 or from the ticker 10 is temporarily stopped, the slippage arrangement indicated by the discs 30 and 32 has been arranged for. By properly adjusting the tension of the spring 35, the slightest retardation of the supply of tape, as the latter is fed to the machine, will be sufficient to hold back the rotation of the wheel 17 or stop the same entirely. Such stoppage of the wheel 17 will not impair the subsequent smooth operation of the machine as soon as the supply of tape is again forthcoming.

It will thus be seen that I have constructed a machine for accomplishing the desired purposes in a simple and expeditious manner and by means of mechanism which is not only compact and simple in construction and nature, but also highly efficient in performing its functions. It is to be particularly noted that no attendance whatsoever is required other than that necessary to withdraw the completed roll and to thread the tape into the machine for the initiation of a new roll.

It will be obvious that changes in the details herein described and illustrated for the purpose of explaining the nature of my invention may be made by those skilled in the art without departing from the spirit and scope of the invention as expressed in the appended claims. It is therefore intended that these details be interpreted as illustrative, and not in a limiting sense.

Having thus described my invention and illustrated its use, what I claim as new and desire to secure by Letters Patent is—

1. In a machine for winding a supply of tape into a spiral roll of gradually increasing diameter, means for frictionally engaging the periphery of said roll over a substantial arc to rotate and position the latter, said means including a driven belt and an opposing idler both mounted to yield radially as the roll grows in diameter, and means engaging the supplied tape for advancing the same at uniform speed onto said rotating periphery.

2. In a machine for winding a supply of tape into a spiral roll of gradually increasing diameter, means for frictionally engaging the periphery of said roll over a substantial arc to rotate and position the latter, said means including a driven belt and an opposing idler, yieldable means for carrying said belt and said idler to permit radially outward movement of both as the roll grows in diameter, and means engaging the supplied tape for advancing the same at uniform speed onto said rotating periphery.

3. In a machine for winding a supply of tape into a spiral roll of gradually increasing diameter,

means engaging the supplied tape for advancing the same at uniform speed onto the periphery of said roll, a yieldable driven means for frictionally engaging said periphery over a substantial arc to 5 rotate and position said roll, and an opposing yieldable idler also frictionally engaging said periphery.

4. In a machine for winding a supply of tape into a spiral roll of gradually increasing diameter, 10 means engaging the supplied tape for advancing the same at uniform speed onto the periphery of said roll, and yieldable means for frictionally engaging said periphery over a substantial arc to rotate and position said roll; said yieldable means 15 including a belt and a yieldable opposing idler, a pair of pulleys for said belt, one of said pulleys being positively driven, and a frame carrying said pulleys and pivotable around the axis of one thereof. 20 5. In a machine for winding a supply of tape into a spiral roll of gradually increasing diameter, means engaging the supplied tape for advancing the same at uniform speed onto the periphery of said roll, and yieldable means for frictionally engaging said periphery over a substantial arc to 25 rotate and position said roll; said yieldable means comprising a belt, a pair of pulleys for said belt, and means for yieldably urging said pulleys apart to tension said belt, whereby the latter will 30 form to the constantly changing curvature of said periphery.

6. In a machine for winding a supply of tape into a spiral roll of gradually increasing diameter, 35 means engaging the supplied tape for advancing the same at uniform speed onto the periphery of said roll, and yieldable means for frictionally engaging said periphery over a substantial arc to rotate and position said roll; said yieldable means comprising a belt, a pair of pulleys for said belt, 40 a frame carrying said pulleys and pivotable around the axis of one thereof, and yieldable means for pressing said frame toward said roll.

7. In a machine for winding a supply of tape into a spiral roll of gradually increasing diameter, 45 means engaging the supplied tape for advancing the same at uniform speed onto the periphery of said roll, and yieldable means for frictionally engaging said periphery over a substantial arc to

rotate and position said roll; said yieldable means comprising a belt, a pair of pulleys for said belt, a frame carrying said pulleys and pivotable around the axis of one thereof, and means for yieldably urging said pulleys apart to tension said 80 belt.

8. In a machine for winding a supply of tape into a spiral roll of gradually increasing diameter, means engaging the supplied tape for advancing the same at uniform speed onto the periphery of said roll, and yieldable means for frictionally engaging said periphery over a substantial arc to rotate and position said roll; said yieldable means comprising a belt, a pair of pulleys for said belt, a frame carrying said pulleys and pivotable around 85 the axis of one thereof, yieldable means for pressing said frame toward said roll, and means for yieldably urging said pulleys apart to tension said belt.

9. In a machine for winding a supply of tape into a spiral roll of gradually increasing diameter, means engaging the supplied tape for advancing the latter at substantially uniform speed, means comprising a pair of complementary arcuate elements for deflecting the end of the advanced tape 100 back upon itself to form the nucleus of said spiral roll, and yieldable means for frictionally engaging the periphery of said roll to rotate and position the same, said yieldable means comprising a belt, a pair of pulleys for said belt, a frame 105 carrying said pulleys and pivotable around the axis of one thereof, yieldable means for pressing said frame toward said roll, means for yieldably urging said pulleys apart to tension said belt, and means for driving said belt at a substantially uniform speed which is substantially equal to the 110 speed of said advancing means.

10. In a machine for winding a supply of tape into a spiral roll of gradually increasing diameter, means for frictionally engaging the periphery of 115 said roll to rotate and position the latter, said means including a positively driven device and an opposing idler both being mounted to yield radially outwardly as the roll grows in diameter, and means engaging the supplied tape for advancing 120 the same at uniform speed onto said rotating periphery.
